(57) **CLAIM**

The ornamental design for a set of earbuds, as shown and described.

DESCRIPTION

FIG. 1 is a perspective view of a set of earbuds showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, in an alternate position;

FIG. 9 is a front view thereof with one earbud worn on the user's ear; and,

FIG. 10 is a front view thereof with the set of earbuds hung around the user's neck.

The claimed design is defined by the shaded surfaces; the broken lines depict environment that forms no part of the claimed design.

1 Claim, 7 Drawing Sheets(56)
